UNITED STATES PATENT OFFICE.

WILLIAM ALEXANDER FRASER, OF GEORGETOWN, ONTARIO, CANADA.

PRESSURE FLUSHING DEVICE FOR CLOSETS.

1,099,032.

Specification of Letters Patent. Patented June 2, 1914.

Application filed November 29, 1912. Serial No. 734,023.

To all whom it may concern:

Be it known that I, WILLIAM ALEXANDER FRASER, of the town of Georgetown, in the county of Halton, in the Province of Ontario, Canada, have invented certain new and useful Improvements in Pressure Flushing Devices for Closets, of which the following is the specification.

My invention relates to improvements in pressure flushing devices for closets, and the object of the invention is to devise an extremely simple pressure flushing device for closets capable of having a disinfecting fluid used therewith in order to provide the flushing water therewith.

My invention consists of a flushing receptacle provided with a suitable ball valve, the parts being constructed and arranged as hereinafter more particularly explained.

Figure 1, is a side elevation of my improved flushing device. Fig. 2, is a vertical section. Fig. 3, is a vertical section at right angles to Fig. 2. Fig. 4, is a detail of the operating lever.

In the drawings like letters of reference indicate corresponding parts in each figure.

A is the top of a closet bowl and B is the receptacle, which is fastened to the top A by a flange B' through which extend suitable bolts B² into the top of the bowl A. The valve chamber B is provided with a curved portion B³ at one side, an upper curved portion B⁴ and a curved portion B⁵ opposite the curved portion B³. The curved portions B⁴ and B⁵ terminate in a flange B⁶ to which is secured a circular plate C internally threaded and into which extends the threaded end of the inlet pipe D.

B⁸ is an inwardly extending flange upon which rests a yielding seat E preferably of rubber.

F is the ball valve.

G is the operating lever, which is operated through a handle H.

I is a sanitary device, which is connected by a pipe I' to the valve chamber B, and by a pipe I² to the passage-way B⁹ leading down into the bowl.

The operation of my sanitary device I do not describe as it forms the subject matter 50 of a separate application bearing even date herewith. It is sufficient to say that the water passes up through the pipe I' into the sanitary device, is controlled by a valve and passes down permeated with the sanitary 55 fluid through the pipe I² into the passage-way B⁹ leading to the bowl.

The shifting lever G is made as shown in Fig. 4. The spindle of the handle H passing through the slots G'. The shifting lever is provided with a stop G² to limit its backward throw and a lug G³ to operate against the ball to primarily unseat it to relieve the pressure. The end edge G⁴ forms a final means of throwing the ball 65 into the position shown in dotted lines. It will be noticed that the lever G is dished and it will be consequently understood that when the water passes downwardly between the ball and the lever it serves to help to 70 quickly restore the lever to its normal position on account of the pressure that the water will exert on the dish form.

The operation of my invention is as follows: The lever G is manipulated so that the 75 lug G³ first acts on the ball and temporarily relieves the pressure. The edge G⁴ of the lever then contacts with the ball and throws it into the position shown in dotted lines in Fig. 2, thereby allowing the full pressure 80 of the water to pass through the flanged orifice B⁸. Upon the release of the handle H the lever G assumes its normal position being helped thereby by the pressure of the water on the dished surface and the ball is 85 likewise by the suction and pressure restored to the normal position on its seat. Before the ball is fully seated the water being at a very slight pressure passes through the pipe I' into the sanitary device and 90 back through the pipe I² into the passage-way B⁹ leading to the bowl, such water being surcharged with the disinfecting fluid or chemical in the sanitary receptacle or device therefor.

From this description it will be seen by

this form of flush for closets I eliminate all flushing tanks and obtain the pressure direct from the main.

What I claim as my invention is:

- 5 The combination with the valve chamber having a suitable discharge orifice and a ball valve for said orifice, of a valve shifting lever of dished form, an operating handle

therefor and a limiting lug at the upper end of the lever, and a valve opening lug near 10 the lower end in the dished portion, as and for the purpose specified.

WILLIAM ALEXANDER FEASER.
